UNITED STATES PATENT OFFICE.

WILLIAM E. CHAMBERLAIN, OF PROVIDENCE, RHODE ISLAND, ASSIGNOR
OF ONE-HALF TO EDGAR G. WINDSOR, OF SAME PLACE.

APPARATUS FOR LIGHTING THE PLATFORMS AND STEPS OF RAILWAY-CARS.

SPECIFICATION forming part of Letters Patent No. 254,091, dated February 21, 1882.

Application filed May 17, 1881. (No model.)

To all whom it may concern :

Be it known that I, WILLIAM E. CHAMBERLAIN, of the city and county of Providence, in the State of Rhode Island, have invented certain new and useful Improvements in Apparatus for Lighting the Platforms and Steps of Railway-Cars; and I do hereby declare that the following specification, taken in connection with the drawings furnished and forming a part of the same, is a clear, true, and complete description of my invention.

Heretofore various arrangements of lamps and reflectors have been devised for attaining the end sought by me. In most cases, however, the lamps have been located within the car and arranged by means of a reflector over the platform to more or less deflect a portion of the light; but, so far as my experience goes, the lighted horizontal area resulting therefrom is not sufficiently extensive to completely obviate the liability of passengers to leave the lower step when over a culvert or trestle-work or when on a bridge. In some cases lamps have been heretofore located in the hood of the car; but, so far as my knowledge extends, they have been so arranged as to also cast their light into the car near the roof or horizontally rearward, or, as in street-cars, for also illuminating a box-sign indicating the route to which said cars belong, and such prior arrangements of lamps cause more or less of the platform and steps to be so shadowed as to fail in securing the degree of safety which I deem of great importance.

My invention consists in the combination, with the hood of a car, of a lamp located centrally therein, and surrounded by a conical or inclined reflector, which casts reflected light over an area greater than the entire platform and its steps, and also so as to include in said lighted area the platform of an adjacent coupled car. This last-named capacity is found to be specially valuable on very dark nights, because two adjacent lamps on separate cars fully blend their reflected light, and thereby more thoroughly expose the coupling-space, the platform, and the steps, and include within the

illuminated horizontal area a very considerable space beyond the cars, on each side thereof. By this arrangement, however, when the night is not very dark a single lamp will serve for two platforms.

To more particularly describe my invention, I will refer to the accompanying two sheets of drawings, in which—

Figure 1, Sheet 1, is a sectional view of a portion of a car-hood having a lamp and reflector mounted therein in accordance with my invention, the reflector being shown in central vertical section. Fig. 2, Sheet 1, is an end view of a car with the hood in section and the lamp and reflector applied thereto. Fig. 3, Sheet 2, is a side view of a car with its hood partially broken away to disclose the lamp and reflector in position.

The lamp A and globe B are of the usual type. The reflector C is here shown to be conical in form, and its upper or small end is attached to the usual chimney or cowl, D, and at its lower end it is attached to the under side of the hood E by means of a flange. The reflector is preferably conical, as shown; but it may be four-sided and inclined at the angle, substantially as shown, whereby the downward and lateral rays on the lines F and the rearward or forward rays on the line G will illuminate a horizontal area embracing the platform H and extending beyond the lowest of the steps I on each side, and also embracing the platform of an adjacent coupled car, as indicated in Fig. 3.

Having thus described my invention, I claim as new and desire to secure by Letters Patent—

The combination, substantially as described, of a car-hood, a lamp mounted centrally therein, and an inclined reflector surrounding said lamp, having its angles of reflection arranged, as described, with special reference to lighting an area extending beyond the end of the platform and the steps thereof, as set forth.

WILLIAM E. CHAMBERLAIN.
